[57] CLAIM

The ornamental design for a fishing lure, as shown and described.

DESCRIPTION

FIG. 1 is a top plan view of a fishing lure, showing my new design;

FIG. 2 is a bottom plan view thereof;

FIG. 3 is a front elevational view thereof;

FIG. 4 is a rear elevational view thereof;

FIG. 5 is a right side elevational view thereof;

FIG. 6 is a right side elevational view with the hook rotated 180 degrees;

FIG. 7 is a top plan view of a second embodiment;

FIG. 8 is a bottom plan view thereof;

FIG. 9 is a front elevational view thereof;

FIG. 10 is a rear elevational view thereof;

FIG. 11 is a right side elevational view thereof;

FIG. 12 is a right side elevational view with the hook and weed guard rotated 180 degrees;

FIG. 13 is a top plan view of a third embodiment;

FIG. 14 is a bottom plan view thereof;

FIG. 15 is a front elevational view thereof;

FIG. 16 is a rear elevational view thereof;

FIG. 17 is a right side elevational view thereof;

FIG. 18 is a right side elevational view with the hook rotated 180 degrees;

FIG. 19 is a top plan view of a fourth embodiment;

FIG. 20 is a bottom plan view thereof;

FIG. 21 is a front elevational view thereof;

FIG. 22 is a rear elevational view thereof;

FIG. 23 is a right side elevational view thereof; and,

FIG. 24 is a right side elevational view with the hook and weed guard rotated 180 degrees.
